CUTLERY HOLDER

James L. Hvale, Chicago, Ill., assignor to Ekco Products Company, Chicago, Ill., a corporation of Illinois

Application December 12, 1958, Serial No. 53,746

Term of patent 14 years

(Cl. D44—29)

Fig. 1 is a top perspective view of a cutlery holder showing my new design.

Fig. 2 is an enlarged top plan view thereof.

Fig. 3 is a side elevational view thereof.

Fig. 4 is a second side elevational view taken from the side of the holder opposite to that shown in Fig. 3.

Fig. 5 is an end elevational view of the holder as it appears from the righthand end of the article as shown in Fig. 4.

Fig. 6 is an end elevational view as the holder appears when viewed from the left end of the holder as shown in Fig. 4.

The textured material shown fragmentarily at the right in Figs. 1 and 2 is continued throughout the area outlined by dot-dash lines. Conventional knife blade slots are shown in broken lines for purposes of illustration.

I claim:

The ornamental design for a cutlery holder, as shown and described.
